(57) **CLAIM**

The ornamental design for an orifice mount for high-pressure fluid jet systems, as shown and described.

DESCRIPTION

FIG. 1 is a front perspective view of an orifice mount for high-pressure fluid jet systems, showing our new design. FIG. 2 is a side elevational view thereof, all other side, front, and rear elevational views being identical.

FIG. 3 is a top plan view thereof.

FIG. 4 is a bottom plan view thereof.

FIG. 5 is a front perspective view of an alternative embodiment of an orifice mount for high-pressure fluid jet systems, showing our new design.

FIG. 6 is a side elevational view thereof, all other side, front, and rear elevational views being identical.

FIG. 7 is a top plan view thereof; and,

FIG. 8 is a bottom plan view thereof.
